(57) **CLAIM**

The ornamental design for a dashboard for vehicle, as shown and described.

DESCRIPTION

FIG. 1 is a front perspective view of a dashboard for vehicle showing my design;

FIG. 2 is a front view thereof;

FIG. 3 is a first enlarged front view of a portion of the dashboard for vehicle of FIG. 2;

FIG. 4 a second enlarged front view of a portion of the dashboard for vehicle of FIG. 2;

FIG. 5 is a third enlarged front view of a portion of the dashboard for vehicle of FIG. 2;

FIG. 6 is a fourth enlarged front view of a portion of the dashboard for vehicle of FIG. 2; and,

FIG. 7 a fifth enlarged front view of a portion of the dashboard for vehicle of FIG. 2.

The broken lines in the drawings illustrating portions of the dashboard for vehicle form no part of the claimed design.
